UNITED STATES PATENT OFFICE.

WILLIAM A. O'TOOLE, OF PITTSBURGH, PENNSYLVANIA.

LOCOMOTIVE-DRIVE-BOX WEDGE ASSEMBLY.

Application filed December 31, 1926. Serial No. 158,232.

The present invention relates to locomotive drive boxes and more particularly to an adjustable wedge assembly therefor, and constitutes a specific improvement on the construction shown in my prior Patent No. 1,580,526, dated April 13, 1926.

In the construction shown in my said patent there is a wedge interposed between the driving box of the locomotive and the pedestal in which the driving box is slidably mounted. The wedge is yieldably supported on a spring which is carried at the top of a non-rotatable bolt whose threaded shank is received in a threaded sleeve rotatably mounted in the pedestal brace of the locomotive frame.

It has been found by experiment that any spring which can be fitted into the relatively small space between the lower end of the driving box wedge and the top of the bolt and which is heavy enough to support the weight of the wedge against the thrust of the drive box will not give any very extensive movement between its fully compressed or solid position and its fully expanded position. In order to secure the most satisfactory results, it is necessary that the spring shall provide for a relatively considerable movement of the wedge before the spring has expanded from a fully compressed to a fully extended position.

According to the present invention, the same general construction as that shown in my said patent is employed, but the arrangement is modified to permit of the use of the so-called Bellville type of spring. This type of spring consists merely in a series of oppositely dished discs of spring metal. Such a spring will support a maximum load with a maximum amount of expansion.

The invention may be readily understood by reference to the accompanying drawings, in which

Figure 1 is a view partly in section and partly in elevation, showing the outer face of the driving box wedge in elevation and showing the lower part of the wedge and the supporting means therefor in section;

Figure 2 is a perspective view of the lower end portion of the wedge;

Figure 3 is a side elevation of the supporting bolt showing the upper end thereof in section, and

Figure 4 is a top plan view of the bolt shown in Figure 3.

Inasmuch as the general arrangement and construction of parts is similar to that shown in my said patent, the parts have not been illustrated in connection with the complete driving box assembly, such assembly being clearly shown in Figure 1 of my said patent.

In the drawing, 2 designates the pedestal brace of the locomotive frame, 3 is the inferiorly threaded sleeve passing through the pedestal brace and having a flange 4 at its upper end and having a threaded lower end portion on which is carried a lock nut 5. The lower extremity of the sleeve is squared to facilitate the turning thereof by a wrench, such squared portion being designated 6. A guard 7 is preferably secured to the pedestal brace for protecting the lower extremity of the sleeve. The under-surface of the flange 4 is preferably provided with projections 8 that cooperate with recesses in the surface of the pedestal brace to normally hold the sleeve against rotation, as fully explained in my said patent.

Screwed into the sleeve 3, which is inferiorly threaded, is the threaded shank of a supporting post or bolt 9 having a square or suitably non-circular enlarged head portion 10. In the top of the head portion 10 is a relatively deep socket 11. The sides of the socket are slotted at two diametrically opposite points, as indicated at 12, such slots extending down into the sides of the socket approximately half of the depth thereof. Received in the socket 11 is a so-called Bellville type spring 13. This spring consists merely of a series of reversely arranged discs or washers of spring metal.

The non-circular head portion 10 of the bolt is received in a transverse slot 14 in the lower portion of a driving box wedge 15 having flanges 16 at each side thereof. The flanges 16 preferably terminate above the lowermost end of the wedge, providing shoulders at 17. Projecting down from the transverse slot 14 in the lower part of the wedge is a tongue 18 which is adapted to fit into and be received in the slots 12 in the head portion of the bolt. This tongue rests on the top of the Bellville type spring 13 so that as the spring expands it will urge the wedge 15 upwardly.

In the sides of the slot 14 below the head 10 of the bolt are flanges 19 for cooperation with the under-surface 20 of the head 10 of the bolt, for limiting the relative sliding 110

movement between the wedge and the head of the bolt.

Screwed on to the threaded shank 9 of the bolt is a follower 21 which is substantially U-shaped. This follower serves to indicate the distance which the spring 13 has expanded so that a mechanic can quickly tell when it is necessary to turn the sleeve 3 to set the bolt 9 up again to put the spring under further compression. The nature of this indication is fully explained in my said patent. The amount which the spring has expanded is indicated by the distance between the upper end portions 21^a of the follower 21 and the shoulders 17 of the wedge. When the spring is compressed solid the shoulders 17 are substantially in contact with the upper ends 21^a of the follower 21. As the spring expands and the wedge moves upwardly, due to wear which develops in the driving box wedge, the distance between 17 and 21^a increases. If the mechanic knows that the maximum expansion of the spring is for instance seven-eighths of an inch he can readily tell when it is necessary to set up the bolt 9.

The advantages of the invention resides in the use of a Bellville type spring in the confined space and between the adjusting post and the driving box wedge so that the greatest possible amount of free action can be secured with the necessary resistance to the weight of the wedge, and support it against the thrust of the driving box. A Bellville or multiple disk type of spring of a convenient diameter for a locomotive drive box wedge will have a much greater free action with a sufficient resistance to the thrust and weight to which it is subject, than a coil or volute spring of a considerably greater diameter. It, therefore, becomes apparent that the present invention renders the assembly shown in my prior patent far more efficient without increasing the cost of the assembly and while securing all of the advantages obtained by the compact nature of the assembly shown in my said patent.

The provision of the slots 12 in the head 10 and the provision of the tongue 18 on the wedge allows the spring to be confined so that the discs can not become displaced and at the same time provides for the resilient support of the wedge on the springs. The depth of the slots 12 is substantially equal to the maximum reaction of the spring.

In the normal operation of the invention the post or bolt 9 is set up to a position where the tongue 18 of the wedge compresses the springs, holding wedge sufficiently tight, while permitting of still further compression to offset the dropping of wheel below running line. As wear develops in the driving

box wedge, the wedge is urged up by the expansion of the spring. When the full amount of expansion has taken place, and the amount of expansion can be determined at any time without taking the assembly apart, the bolt 9 is again set up to compress the spring to its former position.

It will be understood that I have shown and described a preferred embodiment of my invention, but that the invention may be otherwise embodied and various changes and modifications made in the construction and arrangement of parts within the contemplation of my invention and under the scope of the following claims.

I claim:

1. An adjusting mechanism for drive box wedges including an interiorly threaded sleeve, a bolt threaded into the sleeve, and a multiple disk type of spring retained on the upper end of the bolt. 70

2. An adjusting screw mechanism for drive box wedges including a vertically adjustable bolt having a socket in the upper end thereof, and a multiple disk type spring in the socket. 85

3. An adjusting screw mechanism for drive box wedges including a vertically adjustable post having a socket at the upper end thereof, the sides of the socket being slotted, and a multiple disk type of spring in the socket. 90

4. A driving box wedge assembly including a wedge, an adjustable post, and a multiple disk type of spring interposed between the post and the wedge. 95

5. An adjustable wedge assembly for locomotive drive boxes including a wedge having a transverse slot in the lower end thereof, a post having a non-circular head slidably received in the slot, a multiple disk type of spring mounted in the upper end of the post, and means for adjusting the post vertically. 100

6. An adjustable wedge assembly for locomotive drive boxes including a wedge having a slotted lower end portion and having a tongue in the top of the slot of such lower end portion, a post having a non-circular head slidably received in the slot in the lower end of the wedge, said post having a non-circular head slidably received in the slot in the head portion thereof, the sides of the socket being slotted at two diametrically opposite points for receiving said tongue, and a multiple disk type of spring in the socket. 110

7. An adjustable wedge assembly for locomotive drive boxes including a wedge, a post slidably and non-rotatably engaging the wedge, and a multiple disk type of spring operatively interposed and confined between the wedge and the post. 115

In testimony whereof I have hereunto set my hand.

WILLIAM A. O'TOOLE.
